RIFLE GRENADE CLINOMETER

Ernest E. Linsert, United States Marine Corps

Application April 25, 1930. Serial No. 447,392

2 Claims. (Cl. 33—207)

(Granted under the act of March 3, 1883, as
amended April 30, 1928; 370 O. G. 757)

My invention relates broadly to a rifle grenade clinometer and more particularly to a device that will satisfactorily solve the problem of procuring accuracy in firing rifle grenades.

5 An object of my invention is to provide a rifle grenade clinometer that once attached to the rifle may be left on the rifle without interfering with the normal firing of the rifle.

10 A further object of my invention is to provide a device that enables an individual firing a grenade from a rifle to hit within a radius of one yard from the target, thus eliminating guess work now employed in the firing of a grenade from a rifle and thereby making a weapon of uncertainty one 15 of unfailing accuracy.

Another object of my invention is to provide a rifle grenade clinometer that incorporates the feature of interchangeability of rotary range scales, making it adaptable to varying weights of grenades and various kinds of ammunition, by the 20 simple process of inserting different rotary range scales.

25 A further object of my invention resides in constructing a rifle grenade clinometer that is not involved in its operation, easy to manufacture and not difficult to replace parts; simplicity with effectiveness governing the manufacture and use of the device.

It is also an object of my invention to provide 30 a device that is rugged, of light weight, and can be carried handily in its carrying case attached to the rifle grenadier's cartridge belt.

With the above and other objects in view, the 35 invention consists in the construction, combination and arrangement of parts as will be described more fully hereinafter.

Reference is to be had to the accompanying drawings forming a part of the specification, in which like reference characters indicate corresponding parts throughout the several views, and in which:

Figure 1 is a side elevation of my improved device shown partly in section;

Figure 2 is a plan view of my improved device;

40 Figure 3 is an end view of my improved device;

Figure 4 is the application of my improved device on a rifle.

Referring more particularly to the drawings, 45 indicates a body member or base to which is secured by means of a hinge 11 a top or rotary range scale holder 12. Inserted in the holder 12 and a portion of the body 10 is a rotary range scale 13 that is held against displacement by and revolves on a flange 14 riding in a groove 15 of the holder 11 and body 10. A flexible leaf spring 16 secured

by screws 17 to the base 10 keeps the holder 12 firmly down in the closed position thereby holding the scale 13 movably in position.

50 Affixed by countersunk screws 18 to the base 10 are clips 19 that are adapted to snap and fit around a stock 30 of a rifle 20 just above the lower band 21 of the rifle 20. A band hook 22, an integral part of the base 10, fits around the lower band screw of the rifle 20 and prevents the clinometer from slipping.

55 A notch 23 is cut in the holder 12 to be used as a reference point when setting the rotary range scale 13. A level 24 is an integral part of the scale 13 and is mounted with its longitudinal axis perpendicular to the axis of rotation of the scale 13, in order that it may be used as a handle 60 to rotate the scale 13. The level 24 is provided with a level vial 25 that may be replaced if broken, by removing a level holder plug 26 threaded into one end of the level 24. Centering lines 31 are suitably marked on the vial 25.

65 The rotary range scale 13 is shown for purpose of illustration as being graduated into divisions, as at 27, each of which represents 25 yards in horizontal range, and is graduated from maximum to the zero range of the grenade in each direction from the maximum graduation on the scale, so that decreased range may be obtained by either raising or lowering the muzzle 70 of the rifle. For example, assuming a maximum range of 300 yards corresponding to an elevation of 45 degrees, a range of say 200 yards may be obtained by firing at either a greater or less elevation. According to which is desired, the appropriate graduation is aligned with the notch 75 23, and the proper elevation of the rifle determined by centering the level-bubble.

80 Different range scales are necessary for each type of grenade depending particularly upon the weight of the grenade. The scales 13 can be readily shifted by opening the holder 12 on the hinge 11. Although I have marked the range scale in yards, I desire it to be understood that the scale can be marked in miles, degrees or any other suitable scale.

85 In the practical use of my improved device the rifle grenade clinometer is snapped over the stock of the rifle, and then moved toward the butt of the rifle until the lower band hook 22 is firmly engaged with the lower band screw of the rifle. The clinometer is then used for laying the rifle when firing grenades.

90 To lay the rifle for any range the rotary range scale 13 is turned by means of the level 25 until the desired range marking is opposite the notch 105 110

23 cut in the rotary range scale holder 12. When the level-bubble is midway between the lines 31 on the level vial 25 the grenade if fired will fall at the range indicated.

5 The rifle grenade clinometer is so designed and constructed that the rifle may be used with the clinometer attached during ordinary firing of the piece. Because of its position on the stock, the grenadier is not prevented from firing his piece normally, and can shift from grenadier to rifleman and vice versa without the slightest delay. The chances are slight of the clinometer's being jarred from position on the rifle stock, but should this occur, the grenadier should slip it back into proper position before adjusting the rotary range scale or leveling the bubble.

10 It will be understood that the above description and accompanying drawings comprehend only the general and preferred embodiment of my invention, and that various changes in construction, proportion and arrangement of parts may be made within the scope of the appended claims, and without sacrificing any of the advantages of my invention.

15 The herein described invention may be manufactured and used by or for the Government of the United States for governmental purposes without the payment to me of any royalties thereon.

What I claim is:

1. A grenade clinometer adapted to be attached to a rifle comprising a base, means for attaching said base to the rifle, a rotary member, snap means adapted to rotatably mount said member to the base and to permit quick and easy displacement of the member from the base, a range scale integral with said member and extending out laterally from said base and mounting means, and a spirit level secured to said scale whereby correct angles of elevation of said rifle are determined for ranges designated on the scale.

10 2. A grenade clinometer adapted to be attached to a rifle comprising a base, a rotary member, a hinged top rotatably mounting said member to the base, a spring secured to the base and bearing against the top so that the member may be easily removed, a range scale integral with said member and extending out from said base and top, a level mounted on the side of said scale, whereby predetermined ranges may be set with regard to a reference point by said scale and correct angles of elevation may be determined by said level without moving the rifle from its firing 90 position, and clips secured to said base for detachably securing the clinometer to the rifle.

ERNEST E. LINSERT.
